(57) **CLAIM**

The ornamental design for a bluetooth adaptor, as shown and described.

DESCRIPTION

FIG. 1 is the front perspective view of a bluetooth adaptor showing our new design;

FIG. 2 is the rear perspective view thereof;

FIG. 3 is the front view thereof;

FIG. 4 is the rear view thereof;

FIG. 5 is the left-side view thereof;

FIG. 6 is the right-side view thereof;

FIG. 7 is the top plan view thereof; and,

FIG. 8 is the bottom plan view thereof.

The broken lines in the drawings depict parts of the bluetooth adaptor that form no part of the claim.

1 Claim, 8 Drawing Sheets
